UNITED STATES PATENT OFFICE.

CHARLES E. BOND, OF SPENCERVILLE, MARYLAND.

SHOCK ABSORBER.

Application filed December 3, 1924. Serial No. 753,569.

This invention relates to shock absorbers or "snubbing" devices for use in motor vehicles in preventing sudden and excessive rebound of the body following the sudden compression of the springs, and in absorbing the forces incident thereto, and thereby preventing shocks. The invention has reference to that type of "snubber" characterized by a spring-actuated rotary drum mounted on one of the relatively movable parts of the vehicle, for example the chassis, and a flexible member or strap connected to and adapted to be wound on the drum and anchored to another relatively movable member of the vehicle, for instance, the axle, the construction and arrangement of the parts being such that on the compression of the vehicle springs and the movement of the chassis toward the axle, the drum will be rotated by its spring and will wind the strap thereon, and on the separation of the chassis from the axle, due to the rebound or expansion of the vehicle springs, such separating movement will be resisted by the drum-actuating spring, and the sudden rebound of the chassis will be prevented.

The invention is directed to certain improvements in "snubbers" of this type, designed to supplement the action of the drum-actuating spring and offer the greatest resistance to the separating movement of the chassis and axle at the beginning of the expansive action of the vehicle springs, whereby the springs will be robbed of their action in causing excessive rebound of the chassis; and designed to enable the drum to act with the greatest force and effect on the strap in winding the same up at the beginning of the compression of the vehicle springs, whereby the cushioning action of the springs will not be interfered with at the moment of their compression, and whereby the strap will be quickly wound on the drum.

The detailed form and construction of the parts to bring about these results will be fully described in the specification to follow, and the novel features thereof will be set forth in the appended claims.

In the accompanying drawings:

Fig. 1 is a side elevation of my improved device with certain parts broken away to expose the internal construction, the parts being in the position they occupy when the vehicle springs are in normal position. 55

Fig. 2 is a similar view, with the parts in the position they occupy when the vehicle springs are strongly compressed as by roughness of the road.

Fig. 3 is a vertical longitudinal section on the line 3—3 of Fig. 1. 60

Fig. 4 is a similar section on the line 4—4 of Fig. 2.

Fig. 5 is a perspective view of the spring actuated drum and its cooperating member 65 or friction plate by which the drum is shifted axially to produce a braking action thereon.

Fig. 6 is a fragmentary view, in side elevation, of the cooperating ends of the drum 70 and plate showing the position of the parts at the completion of the winding movement of the drum, as they appear in Fig. 2.

Fig. 7 is a similar view showing the position of the parts when the drum begins its 75 unwinding movement at the beginning of the reaction of the springs.

Referring to the drawings:

1 designates a housing or casing comprising a base plate 2 fixed to the chassis frame 30 3 by means of a fastening bolt 4, and a cap plate 5 covering the outer end of the casing and fastened in place by the bolts 6. A journal or stud 7 is fixed to the base plate and extends axially within the casing and 35 has a bearing at its outer end in the cap plate, and an eccentric drum 8 is rotatably mounted on the stud within the casing. This drum is of hollow formation and is provided with a hub 9 disposed eccentrically 40 with relation to the circular peripheral surface of the drum, which hub is formed with a bearing opening receiving the stud, the parts being so formed and related that while the drum will be capable of rotation on the 45 stud, it may also shift axially of the stud, the purpose of which will presently appear. A strap 10 has one end fixed to the periphery of the drum as at 11, Figs. 1 and 2, and extends outwardly through an open- 100

ing 12 in the side of the casing and has its other end fixed to the axle 13 of the vehicle, the casing being formed on its interior at the side of the drum with a curved plate 5 formed with a bearing surface 14 against which the strap bears and over which it travels as it is wound on and unwound from the drum. A coiled torsion spring 15 surrounds the hub 9 within the drum and has 10 one end fixed to the base plate 2 as at 16, and has its other end fixed to the drum as at 17, the tendency of the spring being to rotate the drum in the direction of the arrow in Fig. 1 and thereby wind the strap on the 15 drum from the position shown in Fig. 1 to the position shown in Fig. 2, it being understood that the spring opposes its force to the separation of the chassis frame from the axle when the vehicle springs react after 20 their compression.

The form and relation of the drum, bearing surface 14 and the point of connection of the strap with the drum, are such that when the strap has been unwound from the 25 drum as shown in Fig. 1, the longest radius of the drum will be at the top, and the strap will be held free of the inner portion of the bearing surface 14 and the latter will therefore offer the least resistance to the movement of the strap thereover when the strap is wound on the drum; and when the strap has been wound on the drum as shown in Fig. 2, the longest radius of the drum will be at the bottom, and the strap will engage 30 throughout the full extent of the bearing surface and the latter will offer the greatest resistance to the movement of the strap thereover in the unwinding operation. Due to this construction, relation and form of 35 the parts, the greatest resistance to the rotation of the drum will be offered at the moment when the vehicle springs begin to react after their compression, and the sudden rebound of the body of the vehicle will be 40 prevented; and the least resistance will be offered to the rotation of the drum, and the latter will be permitted to act with its greatest leverage on the strap, when the vehicle springs are being compressed and the chassis 45 frame and axle approach each other.

In order to create a further resistance to the unwinding of the strap from the drum when the vehicle springs react after being compressed, I provide means adapted to be 50 brought into play at the beginning of the unwinding movement and operating to apply a braking action to the rotary movement of the drum. In the present instance the braking action is brought about by shifting the drum axially on its stud and causing the 55 drum to frictionally bind at its end against the adjacent face of the base plate 2 of the casing, and to accomplish this result the following instrumentalities are employed.

60 A friction disk or plate 18 is mounted

loosely on the stud adjacent the cap plate 5 and is provided on its outer face with an annular friction surface 19 adapted to cooperate with an annular friction surface 20 on the inner face of the cap plate, which latter surface is gradually offset towards the upper portion of the plate in such manner that when the opposing friction surfaces are in contact with each other at their lower portions, a slight clearance will be left between them at their upper portions as shown at 75 21, Figs. 3 and 4, the purpose of which will presently appear. On its opposite face the friction plate is formed near its peripheral edge with a cam lug 22 provided with a beveled or wedge surface 23 which merges at one end into the flat face of the plate and which at its opposite end joins the face of the plate in an abrupt shoulder 24. Spaced 80 from the shoulder 24 a short distance circumferentially of the plate, is a stop lug 25 projecting from the face of the same. The adjacent end of the drum 8 is formed with a cam lug 26 provided with a beveled or wedge surface 27 oppositely inclined to the surface 23 and adapted to cooperate therewith, and is further provided with a lug 28, which lug is adapted, in the rotary movement of the drum, to shift between and engage the shoulder 24 and lug 25 on the friction plate. At its opposite end the drum is formed with an annular radial friction braking surface 29 which is adapted, when the drum is shifted on its journal to the 90 right, Figs. 3 and 4, to engage with an annular friction braking surface 30 formed on the inner face of the base plate 2, and by such engagement set up a braking action to 95 the rotation of the drum.

Due to the form and construction of the 105 parts described, in the rotary movement of the drum in one direction, the two beveled surfaces 23 and 27 by cooperating with each other will shift the drum on its stud and cause the braking surface 29 on the drum to engage and bind on the braking surface 30 on the base plate, thereby creating resistance to the rotation of the drum, while in the reverse rotation of the drum, the surfaces 23 and 27 cooperating with each other will permit the drum to be shifted in the opposite direction on its journal and will thereby release the braking pressure of surface 29 on surface 30, so that the drum will be permitted to freely rotate in a reverse direction.

In order that these actions of the drum may be coordinated properly with the winding and unwinding action of the strap, to the end that the braking action on the drum will be applied when the strap is drawn outwardly from the position shown in Fig. 2, and the braking action will be relieved when the drum is operated to wind up the strap from the position shown in Fig. 1, the parts are so disposed and related to each 110 115 120 125 130

other that the beveled surfaces 23 and 27 will be in the positions shown in Fig. 6 when the drum is in the position shown in Fig. 2, in which position of the parts the beveled surfaces 23 and 27 will be opposed to each other but disengaged, and the lug 28 will be adjacent the shoulder 24. When now the drum is rotated in the direction of the arrow in Fig. 7, which occurs when the vehicle 5 springs react and draw the strap out, the surface 27 will ride up on the surface 23 and will shift the drum to the right, and the latter reacting against the friction plate 18 which is caused to bind against the cap plate 10 5, the brake surface 29 on the drum will be engaged with the braking surface 30 on the base plate. In the rotary movement of the drum to produce these actions, the lug 28 on the drum is moved into engagement with 20 the lug 25 on the friction plate and the latter will be carried around with the drum, with the brake surfaces 29 and 30 maintained in engagement with each other, and this relation of the parts will continue as long as 25 the separation of the axle from the chassis continues, and until the parts reach the position shown in Fig. 1 representing the full expansion of the vehicle springs. In this action the movement of the drum is not only 30 retarded by the action of the surface 14 on the strap, by the decreased leverage on which the strap acts in turning the drum, and by the resistance of the drum actuating spring, but also by the braking action due to the co- 35 operation of the braking surfaces 29 and 30.

When now the vehicle springs are compressed and the chassis approaches the axle, the drum actuating spring acts to turn the drum in the direction of the arrow in Fig. 40 6, by which action the lug 28 on the drum will be carried towards the shoulder 24 on the friction plate, and the bevel surface 27 will ride down on the beveled surface 23, thereby relieving the pressure of the braking 45 surface 29 on the braking surface 30 and releasing the drum from the braking action and permitting free rotation thereof in winding up the strap, in which rotation of the drum, the friction disk will be carried 50 around with the drum, with its beveled surfaces separated from each other as shown in Fig. 6. This winding action of the strap is aided by the long leverage of the drum on the strap by reason of the longer radius 55 at the upper portion of the drum, and by reason of the decreased area of the surface 14 engaged by the strap as shown in Fig. 1. The drum will therefore act to wind up the strap with the maximum of speed and with 60 the minimum of resistance to its rotation.

It will be noted on reference to Figs. 2 and 4, that when the strap is wound on the drum and the vehicle springs are under compression, the cooperating beveled surfaces 27 65 and 23 on the drum and friction disk re-

spectively, are at the lower portion of said parts in axial alignment with the point distant from the clearance point 21 between the annular friction surfaces 20 and 22 on the friction disk and cap plate. Due to this fact, 70 when the drum is rotated on the reaction of the vehicle springs, the cooperation of the beveled surfaces 23 and 27 will cause the surfaces 20 and 22 on the cap plate and friction disk to bind at the lower portion of 75 these parts, and the friction disk will be momentarily held against rotation, until, in the continued rotation of the drum, the braking surfaces are brought into action and the lug 28 on the drum engages the lug 25 80 on the disk, whereupon the disk will be carried around with the drum and the engagement of the braking surfaces maintained as before described.

As a result of the clearance 21 before alluded to between the friction disk and cap plate, very slight resistance will be offered to the reactive movements of the vehicle springs in the travel over comparatively smooth roads, since under these conditions 90 there will be but a limited extent of engagement of the disk and cap plate; whereas in the travel over comparatively rough roads, causing the springs to be more strongly compressed and causing the braking action of the drum to be brought into play, the friction disk will be caused to engage the cap plate to a greater extent, which will offer the greatest resistance to the reactive movement 95 of the springs.

Also due to the provision of the said clearance 21, the braking action on the drum is gradually reduced as it moves from the position shown in Fig. 4 to that shown in Fig. 3, thereby avoiding any sudden jerks or 105 shocks in the movement of the drum in releasing the brake.

Having thus described my invention, what I claim is:

1. In a snubber, the combination of an eccentric drum adapted to be rotatably mounted on one member of a vehicle, a strap connected to and arranged to be wound on the drum and adapted to be connected to another member of the vehicle movable to and from the first, a spring acting on the drum to rotate the same and wind the strap thereon, and a fixed friction surface over which the strap travels in its winding and unwinding movements, the form of said surface and its relation to the drum being such that when the members of the vehicle move away from each other and the strap is unwound from the drum, the strap will be disengaged from a portion of said friction surface.

2. In a snubber, the combination of an eccentric drum adapted to be rotatably mounted on one member of a vehicle, a strap connected to and arranged to be wound on the drum and adapted to be connected to

another member of the vehicle movable to and from the first, a spring acting on the drum to rotate the same and wind the strap thereon, and a fixed friction surface over 5 which the strap travels in its winding and unwinding movements, the form of said surface and its relation to the drum being such that when the members of the vehicle move away from each other and the strap is unwound from the drum, the strap will be disengaged from a portion of said friction surface, and when the members of the vehicle move toward each other and the strap is wound on the drum, the strap will be engaged with said friction surface throughout 10 its extent.

3. In a snubber, the combination of an eccentric drum adapted to be rotatably mounted on one member of a vehicle, a strap 20 connected to and arranged to be wound on the drum and adapted to be connected to another member of the vehicle movable to and from the first, a spring acting on the drum to rotate the same and wind the strap thereon, and a fixed friction surface over 25 which the strap travels in its winding and unwinding movements, the form of said surface and its relation to the drum being such that the surface will offer the maximum resistance to the travel of the strap when the drum is rotated to unwind the strap on the separation of the members of the vehicle, and will offer the minimum resistance to the 30 travel of the strap when the drum is rotated 35 to wind the same on the movement of said members toward each other.

4. In a snubber, the combination of a drum adapted to be rotatably mounted on one member of a vehicle, a strap connected 40 with the drum and arranged to be wound thereon and adapted to be connected to another member of the vehicle movable to and from the first, said drum being movable to a limited extent axially and provided with 45 a braking surface, a fixed braking surface in position to be engaged by the braking surface on the drum when the latter is moved axially, a spring acting on the drum to rotate it to wind up the strap when the 50 members of the vehicle move toward each other, and means controlled by the rotary movement of the drum when the members of the vehicle move away from each other, and operating to shift the drum axially and engage 55 the braking surfaces with each other.

5. In a snubber, the combination of a drum adapted to be rotatably mounted on one member of a vehicle, a strap connected to said drum and arranged to be wound 60 thereon and adapted to be connected to another member of the vehicle movable to and from the first, said drum being movable axially to a limited extent, a spring acting on the drum to rotate the same to wind up 65 the strap when the members of the vehicle

move toward each other, means controlled by the rotation of the drum in the opposite direction when the members of the vehicle move away from each other and acting to shift the drum axially, and means brought 70 into operation by the axial shifting of the drum for applying a braking action to the rotation thereof.

6. In a snubber, the combination of a drum adapted to be rotatably mounted on 75 one member of a vehicle, a strap connected to and arranged to be wound on the drum and adapted to be connected to another member of the vehicle movable to and from the first, said drum being movable axially to 80 a limited extent, a spring acting on the drum to rotate the same and wind the strap thereon when the members of the vehicle move toward each other, means controlled by the rotation of the drum on the separation of 85 said members and acting to shift the drum axially and maintain it in shifted position during the reverse motion of the drum, and means brought into action by the axial shifting of the drum for applying a braking action 90 thereto.

7. In a snubber, the combination of a casing adapted to be fixed to one member of a vehicle, a drum rotatably mounted in said casing, a strap connected to and arranged to be wound on the drum and adapted to be connected to another member of the vehicle movable to and from the first, said drum being movable axially to a limited extent, 95 and provided with a braking surface, a braking surface on the casing in position to be engaged by the braking surface on the drum when the latter is moved axially, said drum being provided also with a beveled surface, a spring acting on the drum to rotate the 100 same and wind the strap thereon when the members of the vehicle move toward each other, a friction disk rotatable about the axis of the drum in position to engage the casing and provided with a bevel surface 105 adapted to cooperate with that on the drum, the relation of said beveled surfaces on the drum and friction disk being such that on the reverse rotation of the drum the said beveled surfaces will cooperate with each 110 other and will be shifted axially and engage the braking surfaces with each other. 115

8. In a snubber, the combination of a casing adapted to be fixed to one member of a vehicle, a drum rotatably mounted in said 120 casing, a strap connected to and arranged to be wound on the drum and adapted to be connected to another member of the vehicle movable to and from the first, said drum being movable axially to a limited extent, a 125 braking surface on the casing in position to be engaged by the braking surface on the drum when the latter is moved axially, a spring acting on the drum to rotate the same and wind the strap thereon when the 130

vehicle springs are compressed, a friction disk adapted when the drum is rotated on the reaction of the vehicle springs to cooperate with the casing and drum in shifting the latter axially, said disk being so disposed with relation to the casing that a clearance will be left between it and the

casing at one side of the axis of the drum, when the vehicle springs are in normal position.

10

In testimony whereof I have affixed my signature hereto.

CHARLES E. BOND.
